UNITED STATES PATENT OFFICE

EARL H. WETHERBEE, OF ST. PAUL, MINNESOTA

HOLDER AND CLAMP

Application filed March 29, 1930. Serial No. 439,936.

This invention relates to an improved holder and clamp, particularly adapted for use to adjustably support a receptacle or other article.

5 A further object of the invention is to provide a clamping device comprising a jaw adapted to be engaged with a suitable support and having means thereon for demountably supporting an article such as an ash tray, the jaws of said device being provided with concaved surfaces whereby the jaws may be secured to a cylindrical support such, for example, as the standard of a bridge lamp or the steering post of an automobile.

10 A further object is to provide a clamping device having a wedge-shaped member mounted thereon and adapted for rotary adjustment, said member having a spring bolt engageable with a ratchet to secure the member in an adjusted position and whereby an ash tray or other article supported upon the device may be adjusted to the desired position regardless of the angle of the supporting member to which the clamping device may be attached.

15 Other objects of the invention will appear from the following description and accompanying drawings and will be pointed out in the annexed claims.

20 In the accompanying drawings, there has been disclosed a structure designed to carry out the various objects of the invention, but it is to be understood that the invention is not confined to the exact features shown as various changes may be made within the scope of the claims which follow.

In the drawings:

25 Figure 1 is a vertical sectional view showing the device attached to the edge of a card table;

Figure 2 is a plan view of the device with the receptacle removed;

30 Figure 3 is a view showing a form of receptacle provided with means whereby it may be detachably supported upon the member provided upon the clamping device;

Figure 4 is a view partially in section showing the device attached to a cylindrical support such as the steering post of an automobile;

Figure 5 is a detail sectional view on the line 5—5 of Figure 1, showing the ratchet device for retaining the member in adjusted position; and

Figure 6 is a view on a smaller scale, 55 showing the device attached to the edge of a table.

The novel device featured in this invention comprises a clamp including a fixed jaw 2 and a movable jaw 3. The movable jaw 3 is pivotally connected with a threaded stem 4 received in threaded engagement with a lug 5, provided upon a plate 6 with which the fixed jaw 2 is preferably integrally formed. The plate portion 6 forms the 60 body of the clamping device. The threaded stem 4 is provided with the usual bar 7, whereby it may be rotated to operate the movable jaw 3. In Figure 1, the clamp is shown secured to the rail 8 of a card table 9. 70

The fixed jaw 2 is provided with inclined grooves 11 and correspondingly shaped tongues 12 adapted to be received in grooves 13 provided upon the article to be supported as, for example, the receptacle 14, which may be an ash tray, or some other article which it is desired to support. By thus supporting the receptacle 14 upon the fixed jaw 2, the receptacle may readily be detached from the fixed jaw 2 of the clamp, as shown in 80 Figure 2. The inclined grooves 13 on the receptacle 14 are adapted to receive the tongues 12 on the fixed jaw 2, and the tongues 15 provided upon the receptacle 14 are similarly adapted to be received in the correspondingly shaped grooves 11 provided upon the fixed jaw 2. By the provision of these grooves and tongues upon the fixed jaw and the receptacle, the latter may be quickly attached to and detached from 85 the jaw 2, as will readily be understood by reference to Figures 1, 2, and 3.

In the drawings, a receptacle 14 is shown provided with a small tray 16 at its upper or open end, pivotally connected to the side walls thereof by suitable pivots 17 and 18, the latter being provided with a finger grip as shown in Figure 3. Ashes and cigar butts may be placed in the tray 16, after which the latter may be rotated by the 100

finger grip 18, causing the contents of the tray to drop into the receptacle 14, as will readily be understood.

A feature of the invention resides in the means provided on the plate portion 6 of the clamp for supporting the receptacle when the clamp is secured to an inclined support 19, such as shown in Figure 4, and whereby the receptacle may be positioned in a vertical or upright position regardless of the angularity of the support 19.

A member 21 is rotatably mounted upon the plate 6 by means of a stud 22 having a threaded terminal received in threaded engagement with the plate portion 6, as shown in Figure 1. The member 21 is provided with inclined grooves 23 and tongues 24 corresponding to those provided upon the fixed jaw 2. The grooves 23 and tongues 24 are adapted to be engaged by the tongues 12 and grooves 13, respectively, provided upon the receptacle 14 to detachably support the receptacle upon the clamping device.

A member 21 is adjustably supported upon the plate 6 and is retained in adjusted position by means of an internal ratchet 25 and a spring bolt 26, the latter being slidably mounted in a socket 27 provided in the member 21. An off-set tooth 28 is provided upon the bolt 26 and is shaped to engage the teeth of the ratchet 25, as shown in Figures 1 and 5. A small spring 29 constantly urges the bolt 26 in an outward direction so as to cause the tooth 28 to engage the teeth of the ratchet 25 and thus hold the member 21 in adjusted position upon the plate 6. In Figure 4, the outline of the receptacle 14 is indicated in broken lines, and the receptacle is shown positioned in an upright position, while the support 19 upon which the clamp is secured is angularly disposed.

Figure 6 illustrates the clamp attached to the edge of a table 31. When thus positioned, the member 21 is adjusted so as to bring the spring bolt 26 substantially in alignment with the threaded stem 4, so as to support the receptacle in an upright position, as shown.

The jaws 2 and 3 are provided with concaved faces 32 and 33, respectively, as shown in Figure 1, so that they may grip a cylindrical support such as the one shown in Figure 4 and retain the device thereon without relative movement. The jaws 2 and 3 and also the adjacent face of the plate 6 are preferably lined with a suitable material such as felt 34 to prevent the device from marring the surface of the support to which it may be secured.

The novel clamp herein disclosed has been found very useful in that it provides means whereby a receptacle, or other article such as a tray, may be detachably supported upon the edge of a table, the standard of a bridge

lamp, an automobile steering post, or the instrument board of an automobile, and the receptacle adjusted to the desired position regardless of the position of the support to which it may be attached.

In the drawings, I have shown the novel clamp used as a means for supporting an ash tray or other receptacle but it is to be understood that it may be used as a support for various other articles, which it is desired at times to attach to the edge of a table or other support. The article to be supported upon the clamp must, of course, be provided with the inclined grooves and tongues shown in the drawings.

I claim as my invention:

1. A device of the class described, comprising a plate portion having a fixed jaw at one end thereof and a movable jaw cooperable with said fixed jaw to secure the device to a suitable support, a member mounted on said device and adapted for rotary adjustment, said member having inclined grooves and tongues adapted to be engaged by correspondingly shaped grooves and tongues provided upon an article, whereby said article may be detachably and rotatably supported upon said device.

2. A device of the class described, comprising a plate portion having a fixed jaw at one end and a movable jaw cooperable therewith to secure the device to a support, means on said fixed jaw adapted to detachably support an article, a member mounted on said plate portion and adapted for rotary adjustment, said member having means for detachably supporting an article thereon, and means for locking said member in an adjusted position.

3. A device of the class described, comprising a body portion having a fixed jaw thereon, a complementary jaw movably mounted on said body portion and adapted to cooperate with said fixed jaw to grip a support, said jaws having concaved faces whereby they may grip a cylindrical support, means on said fixed jaw for detachably supporting an ash tray or other article thereon, a member mounted upon said body portion and adapted for rotary adjustment and also provided with means for detachably supporting an article thereon, means for locking said member in an adjusted position upon said plate portion, and the medial planes of said fixed jaw article attaching means and said adjustable member being disposed at substantially right angular relation.

4. A device of the class described, comprising a body portion having a fixed jaw and a movable jaw, adapted to grip a cylindrical support, means on said fixed jaw adapted to detachably support an article such as an ash tray, a member mounted upon said body portion and adapted for rotary adjustment, a spring actuated detent engage-

able with toothed means for locking said member in adjusted position upon said body portion, said member having oppositely disposed inclined grooves and tongues adapted 5 to be engaged by correspondingly shaped grooves and tongues provided upon an article, whereby said article may be detachably supported upon the device.

In witness whereof, I have hereunto set
10 my hand this 25th day of March, 1930.

EARL H. WETHERBEE.
